UNITED STATES PATENT OFFICE.

THOMAS C. DRAKE, OF MALTA, OHIO.

RINGER SYSTEM FOR TELEPHONE-EXCHANGES.

SPECIFICATION forming part of Letters Patent No. 763,971, dated July 5, 1904.

Application filed April 14, 1903. Serial No. 152,500. (No model.)

To all whom it may concern:

Be it known that I, THOMAS C. DRAKE, a citizen of the United States, residing at Malta, in the county of Morgan and State of Ohio, have invented certain new and useful Improvements in Ringer Systems for Telephone-Exchanges, of which the following is a full, clear, concise, and exact description, reference being had to the accompanying drawings, forming a part of this specification.

My invention relates to means for ringing telephone-bells on telephone-lines in which a direct-current type of relay, such as cut-off relays in common battery systems, are connected in multiple or bridge with the bell-winding, the object being to operate the bell and relay simultaneously by means of the same current when calling a subscriber.

Before my invention it has been proposed to bridge a direct-current type of relay with a line-circuit or ground the same from one side of a metallic line-circuit in such a manner as to place the relay-winding in multiple or bridge with the winding of a polarized call-bell of the usual type employed in telephony. In the operation of circuits of this character it is necessary to maintain the relay energized while ringing the call-bell connected in multiple therewith, and as the usual alternating current will only vibrate the relay-armature and not hold it steady the contacts of the relay are not properly made to effect satisfactory operation and ringing. One method of operating such circuits has been to employ a pulsating current, which by its succession of impulses of one polarity through the relay will give more or less satisfactory operation; but this method requires a condenser in the call-bell circuit in order to convert the pulsating current into suitable alternating current for operating the polarized call-bell. According to another method it is proposed to bridge a special alternating-current relay with the alternating-current call-bell, the relay and call-bell being adapted to operate in multiple when ringing over the line-circuit with an alternating-current generator. In accordance with this method the special relay has been designed to operate with either alternating or direct currents, and the construction involved

a massive armature that is withdrawn from the core of the relay-magnet by gravity. The operation of the armature is thus sluggish, and upon ringing through the same with an alternating current the magnetic attraction for the armature is only intermittent and each successive alternation will energize the core to cause the same to grasp the armature before the armature has had time to be withdrawn upon the cessation of the magnetism due to the immediately-preceding alternation. During the passage of a continuous current, however, the armature will be held up to the core, due to a constant magnetic attraction; but when alternating current energizes the relay-winding the armature is held up by means of the intermittent magnetic attraction or pull, the pulsations of which are too rapid to permit the armature to recede from the pole appreciably between the pulsations.

The object of my invention is to provide a simple and satisfactory method of energizing the call-bells and relays simultaneously, so that the call-bell will be rung and the relay's armature held steadily attracted by means of the same energizing-current.

Another object of my invention is to provide a system of ringing which will permit the use of the ordinary type of continuous or steady current relays in systems and circuits which heretofore required a special alternating-current relay.

The object of my invention is attained by connecting an electrical generator of suitable current for ringing a polarized call-bell in series with an electrical generator of suitable current to energize and hold up the armature of a common type of continuous or steady current relay.

To more fully understand my invention, I have illustrated the same in the accompanying drawings, in which—

Figures 1 and 2 illustrate the gist of my invention in its preferred embodiment, wherein in an alternating-current generator and a suitable direct or steady current generator are connected in series and bridged with a continuous-current type of relay and a polarized call-bell of the usual type; and Figs. 3 and 4 are diagrams of commercial switch-

board-circuits with my invention associated therewith.

Referring to Fig. 1, c is a polarized call-bell, in series with which is a resistance c' , 5 adapted to prevent excessive current from interfering with the bell's operation. A desirable way to accomplish the same result is to wind the bell-coils with suitable resistance-wire. A preferable method, however, is to 10 place the call-bell in series with a condenser. The latter method is diagrammed in Fig. 2, where b' is a condenser in series with the call-bell b , the condenser effectually preventing direct current from affecting the bell's polarization and at the same time allowing fluctuating current set up by the ringing-generator to act on the gong-sounding mechanism of the call-bell in a manner well understood.

In Fig. 1, c^2 is a line-circuit represented as a 20 ground-return; but it is obvious that it may be a metallic circuit in so far as the principles of my invention are concerned. Bridged with the line and in multiple with the call-bell c is a direct-current type of relay c^3 . This relay 25 may be employed to efface a line-signal, according to any of the well-known methods, or employed to connect the line-circuit and jack together, as is diagrammed in Figs. 3 and 4. A generator of suitable current to 30 operate the call-bell is represented at c^4 . A suitable source of direct or steady current to actuate the relay c^3 is represented at c^5 , the two generators being connected in series and bridged across the relay and call-bell, as the 35 diagram clearly indicates. In Fig. 2 the circuits are the same as Fig. 1, except that the call-bell is grounded through a condenser instead of through a resistance. In practice the generator c^5 is preferably designed for 40 twenty-cycle alternating current, this being a standard for ringing telephone-bells, and the direct-current generator may be the storage battery employed in common-battery telephone-exchanges. Although the electrical 45 dimensions of the several devices employed are not of the essence of my invention and may be varied considerably, good results have been obtained with the call-bell b wound to one thousand ohms and the condenser b' of 50 two-microfarad capacity, the relay b^3 wound to five hundred ohms, the alternating-current generator b^5 giving eighty volts and the direct or steady current generator b^4 giving forty volts.

55 The characteristics of an ordinary alternating generator for operating telephone-bells are well understood. During the reversal of polarity or change in the direction of current there will be no effective current flowing to 60 energize the relay at certain intervals of each cycle—that is to say, there is a period in each alternation where no current is generated—and when ringing through relays of usual construction with current of this character 65 the armature of the relay will retract

from the pole of the magnet, to be again attracted, however, when the current-wave rises well toward maximum. This results in continuous fluttering and chattering of the relay-armature while ringing and will not operate 70 the contacts properly for maintaining the circuits closed.

Referring to Fig. 3, my invention is associated with a well-known switchboard-circuit. In this circuit a subscriber's line extends in 75 two limbs f, f' to the central station, where the same are connected, respectively, with the movable contact members f^2, f^3 , which are adapted to be actuated by means of the electromagnet f^4 and retracted to normal condition when the electromagnet is not energized. The aggregation of the elements f^2, f^3, f^4, f^5 , f^6, h^3 , and h^4 constitute a cut-off relay. Under the normal condition of the cut-off relay contact member f^2 rests against back contact 80 f^5 and the other contact member, f^3 , rests against back contact f^6 . Between the back contacts are connected a line-relay f^7 in series with an energizing-battery f^8 , which battery is adapted to actuate the line-relay when the 85 resistance across the line-circuit or between the two limbs f, f' is diminished in any suitable manner, usually by connecting a suitable telephone apparatus across the line for talking purposes. For the object of describing 90 my invention I have shown two call-bells g and g' connected from either side of the line to ground. These bells may be wound to high 95 resistance or placed in an equivalent circuit or connected with a condenser in a well-known manner. A line-connection terminal or jack h is adapted to have the thimble h' thereof grounded through the cut-off-relay winding f^4 and the line-spring h^2 thereof connected with front contact h^3 . The thimble h' of the 100 jack is also adapted to be connected with the f side of the line through front contact h^4 and contact member f^2 , and the line-spring h^2 is adapted to be connected with the f' side of the line through contact h^3 and contact member f^3 . There is a suitable call-plug i , connected through cord-strands with the ringing-key, which plug is adapted to be inserted 105 into the line-connection terminal or jack in the act of ringing either of the call-bells. A 110 double ringing-key is diagrammed. The key designated A is connected with and arranged to connect the alternating generator and the direct-current generator or battery with the line-circuit according to the prior art for operating 115 the cut-off relay and one of the call-bells simultaneously. The key designated B is arranged to connect the alternating-current generator and source of steady or direct current with the line-circuit according 120 to my invention, the object, of course, being to actuate the cut-off relay and ring the call-bell, connected in multiple with the cut-off-relay winding, by means of the same energizing-current. When plug i is inserted in 125

jack h , the tip i^6 registers with line-spring h^2 and the sleeve i^3 registers with thimble h' . In the act of ringing call-bell g' the key A is pressed, which distends switch-springs i^2 i^5 5 into contact with back contacts i' i^4 , respectively. Under this condition of the system circuit may be traced from battery j through back contact i' , spring i^2 , sleeve i^3 of plug i , thimble h' of jack h , cut-off-relay winding f^4 10 to ground and back to grounded battery j . The current traversing the circuit of course actuates cut-off relay, whereupon contact members f^2 f^3 disconnect line-relay and battery f^8 and connect limbs f f' of the telephone-line with front contacts h^4 h^3 , respectively. When key A is in position to connect battery j through relay f^4 , alternating-current generator j' is also connected from ground through back contact i^4 , spring i^5 , tip 15 i^6 , and line-spring h^2 of the jack. It will be observed that under this condition of the line direct current will be projected over the f side of the circuit to energize cut-off relay f^4 , while alternating current is projected over the other side, f' , to ring call-bell g' . In this 20 figure I have illustrated a practical method of operating two call-bells on a switchboard-circuit of this character. In this particular circuit the bells may be employed for selective 25 signaling purposes. When ringing over the circuit by means of my invention, the key B is pressed, the key A remaining in normal position, which will maintain the cord-strands continuous to spring i^8 . On depressing key 30 B spring i^8 is distended into contact with back contact i^7 , which contact is grounded through alternating generator j^3 and the direct or steady current generator j , the two generators being connected in series. The winding 35 j^2 represents the primary of a suitable transformer, which is adapted to take current from alternating generator j' or any other suitable source. The winding j^3 represents the secondary of the transformer, which is adapted 40 to give alternating current suitable for operating telephone call-bells. When key A is in normal position and key B is pressed for ringing, the circuit may be traced through battery j , secondary winding j^3 , back contact 45 i^7 , spring i^8 , spring i^2 , sleeve i^3 of plug, thimble h' of jack h , cut-off-relay winding f^4 , which actuates contact members f^2 f^3 , and call-bell g , which is then connected in multiple or bridge with the cut-off relay. Under 50 this condition of the circuit alternating and direct current in series will traverse the circuit and energize cut-off relay in such a manner as to draw up contact members f^2 f^3 and maintain them in contact with the front contacts h^4 h^3 continuously and without flutter or vibration, as would be the case if the direct or steady current j were not connected in series with transformer-winding j^3 . When 55 contact member f^2 is drawn up, a path for ringing-current through call-bell g is pro-

vided, the circuit being through front contact h^4 , contact member f^2 , limb f , and call-bell winding to ground, the call-bell winding and cut-off-relay winding being grounded in multiple and energized by the same current. 70

Fig. 4 is a diagrammatical representation of another well-known switchboard-circuit with my invention associated therewith, the operation of the same being practically identical with Fig. 3 in so far as my invention is concerned. In this circuit the thimble k^2 of jack k is normally disconnected from the line, and the cut-off-relay winding for actuating the relay-armature is grounded from the line-spring side of the circuit. There are two differential windings l and l' on the cut-off relay, one of which, together with line-relay l^2 , is adapted to be cut out when ringing over the line to call a subscriber. Besides the usual call-bell m^2 there is a supplemental call-bell 85 m^3 , adapted to be connected in multiple or bridge with cut-off-relay winding l when ringing over that side of the line with generators arranged according to my invention. When plug n is inserted into jack k and key C is 90 pressed, the circuit is operated in the usual manner according to the prior art—i. e., direct current is projected from battery o through back contact n' , spring n^2 , tip n^3 of plug n , line-spring k' , and one of the differential windings l to ground. The current from battery o operates the relay to cut out line-relay l^2 95 and differential winding l' by drawing up armature l^3 , which breaks contact at l^4 and makes contact at l^5 , this operation connecting 100 thimble k^2 of the jack with the n' side of the line, whereby a path for alternating current is made over the other side of the line through alternator o' , back contact n^4 , spring n^5 , sleeve n^6 of plug n , front contact l^6 , contact member 105 l^7 , limb m' , call-bell m^2 , with return through the earth as diagrammed. When ringing over the circuit by means of my invention, the key D is pressed. The direct or steady current and alternating-current generator in 110 series may be traced from alternator r through direct or steady current source r' , back contact n^7 , spring n^8 , tip n^9 of plug n , line-spring k' , the differential winding l to ground. The circuit may be further traced over limb m 115 and through call-bell m^3 to ground. Under this condition of the system alternating and direct or steady current in series will energize the cut-off relay continuously to hold up armature l^3 and will also operate call-bell m^3 , 120 which is bridged or in multiple with differential winding l .

I do not wish to be limited to the precise circuits and systems herein described, as my invention may be employed with any combination of circuits wherein it is necessary to operate simultaneously a direct or steady current type of relay and a suitable call-bell in multiple; but,

Having described my invention, what I 130

claim as new, and desire to secure by Letters Patent, is—

1. In a telephone system, the combination of a line, a relay bridged with the line and a high-resistance call-bell bridged with the line and in multiple with the relay, and a source of suitable current to actuate the relay in series with a source of suitable current to actuate the high-resistance call-bell, and means to connect the two sources of current in multiple with the call-bell and relay in the act of energizing the relay and call-bell simultaneously, substantially as described.
2. In a telephone system, the combination of a line, a direct-current type of relay and a polarized call-bell bridged with the line, and means to project suitable current over the line to actuate the bell and relay simultaneously, and means consisting of a suitable source of current to actuate the relay, and a suitable source of current to actuate the call-bell, the two sources of current being connected in series with each other and in multiple with the call-bell and relay during the operation of the two elements, substantially as described.
3. In a telephone system, the combination of a line, a direct-current type of relay and a high-resistance polarized call-bell bridged with the line, and means to actuate the relay and call-bell simultaneously in the act of ringing the call-bell, the means comprising a suitable source of current to actuate the relay, and a suitable source of current to actuate the call-bell, the two sources of current being connected in series with each other and in multiple with the call-bell and relay in the act of ringing the call-bell, substantially as described.
4. In a telephone system, the combination of a line, a polarized call-bell bridged with the line and a high resistance in the call-bell circuit, a direct-current type of relay bridged with the line and adapted to be operated when the call-bell is rung, and means to actuate the call-bell and relay in multiple in the use of the line, the means comprising a suitable source of current to actuate the polarized call-bell, and a suitable source of current to actuate the relay, the two sources of current being connected in series with each other and in multiple with the call-bell and relay in the use of the line, substantially as described.
5. In a telephone system, the combination of a line, a polarized call-bell connected with the line and a condenser in the call-bell circuit, a direct-current type of relay bridged with the line and in multiple with the call-bell and adapted to be operated when the call-bell is rung, and means to actuate the call-bell and relay in multiple in the use of the line, the means comprising a suitable source of current to actuate the polarized call-bell, and a suitable source of current to actuate the relay, the two sources of current being connect-

ed in series with each other and in multiple with the call-bell and relay in the use of the line, substantially as described.

6. In a telephone system, the combination with a line-circuit, of a line-signal therefor, a cut-off relay bridged between said line-circuit and ground and adapted when actuated to render the line-signal inoperative, an alternating-current call-bell bridged between said line-circuit and ground and adapted to be actuated in multiple with said cut-off relay, a cord-circuit to establish connection with the line-circuit, an alternating-current generator in the cord-circuit and adapted to be bridged with the call-bell and cut-off relay to actuate both of said elements, and a source of steady current connected in series with the alternating-current generator to maintain the cut-off relay actuated while the alternating ringing-current is reversing, substantially as described.

7. In a telephone system, the combination of a line, a polarized call-bell bridged with the line and means in the bell-circuit to prevent excessive current from passing therethrough, a relay in a bridged circuit with the line and adapted to be acted upon by the ringing-current, a source of alternating current bridged with the line to actuate the call-bell and relay, and a source of direct current in series with the alternating current to energize the relay while the alternating current is reversing, substantially as described.

8. In a telephone system, the combination of a line, a call-bell bridged with the line and a high resistance in the call-bell circuit, a relay bridged with the line, and a source of alternating current bridged with the line to actuate the call-bell and relay in multiple, and a source of direct current in series with the alternating current to energize the relay while the alternating current is reversing, substantially as described.

9. In a telephone system, the combination with a line, of a call-bell bridged with the line and a condenser in the call-bell circuit, a relay bridged with the line and in multiple with the call-bell, and a source of alternating current bridged with the line to actuate the call-bell and relay in multiple in the use of the line, and a source of direct current in series with the alternating current to energize the relay while the alternating current is reversing, substantially as described.

10. In a telephone system, the combination of a line, a polarized call-bell bridged with the line and means in the bell-circuit to prevent excessive current passing therethrough, a relay in a bridged circuit with the line and adapted to be acted upon by the ringing-current, a source of alternating current bridged with the line to energize the call-bell and relay in multiple in the use of the line, and a source of direct current in series with the alternating current to energize the relay when

- the alternating current is *nil*, substantially as described.
11. In a telephone system, the combination with a line, of a call-bell bridged with the line and means in the bell-circuit to prevent excessive current from interfering with the bell's operation, a direct-current type of relay bridged with the line, and means to connect a suitable current for operating the relay and a suitable current for operating the call-bell in series and bridge the same with the line in the use of the line, whereby the call-bell and relay will be operated in multiple, substantially as described.
12. In a telephone system, the combination with a line, of a call-bell bridged with the line and means in the call-bell circuit to prevent excessive current from interfering with the bell's operation, a direct-current type of relay bridged with the line and in multiple with the call-bell, a source of alternating current bridged with the line to actuate the call-bell and relay in multiple in the use of the line, and a source of direct current in series with the alternating current to energize the relay while the alternating current is reversing, substantially as described.
13. In a telephone system, the combination of a line, a call-bell and condenser bridged with the line, a relay bridged with the line, and a source of non-continuous potential bridged with the line to charge and discharge the condenser through the call-bell, and a source of direct current in series with the non-continuous potential to maintain current through the relay when the non-continuous potential is inoperative on the relay, substantially as described.
14. In a telephone system, the combination of a subscriber's line, and a cut-off relay for the line, a call-bell at the subscriber's station connected with the line and means in the call-bell circuit to prevent excessive current from interfering with the bell's operation, a suitable source of current for operating the call-bell and a suitable source of current for operating the relay connected in series with each other and adapted to be bridged with the call-bell and relay in the act of ringing the call-bell, substantially as described.
15. In a telephone system, the combination of a subscriber's line, and a cut-off relay bridged with the line, a polarized call-bell at the subscriber's station connected with the line and means in the bell-circuit to prevent excessive current from interfering with the bell's operation, a suitable source of current for operating the polarized call-bell and a suitable source of current for operating the cut-off relay connected in series with each other and adapted to be bridged with the line in the act of operating the call-bell and relay in multiple, substantially as described.
16. In a telephone system, the combination of a subscriber's line, and a cut-off relay bridged with the line, a polarized call-bell bridged with the line at the subscriber's station, and means in the call-bell circuit to prevent excessive current from interfering with the bell's operation, a source of alternating current bridged with the line for operating the call-bell and relay in multiple in the use of the line, and a source of direct current in series with the alternating-current source to hold up the cut-off relay's armature while the alternating current is reversing, substantially as described.
17. In a telephone system, the combination with a subscriber's line, of a cut-off relay for the line, a polarized call-bell at the subscriber's station and a condenser in the call-bell circuit, means to project suitable current over the line to actuate the call-bell and relay in multiple simultaneously, the means comprising a source of direct current in series with a source of fluctuating current, substantially as described.
18. In a telephone system, the combination with a subscriber's line, of a direct-current type of cut-off relay connected with the line, a polarized call-bell at the subscriber's station and a high resistance in the call-bell circuit to prevent excessive current from interfering with the bell's operation, a source of direct current in series with a source of fluctuating current and means to connect the same in multiple with the call-bell and cut-off relay in the use of the line, whereby the call is rung and the cut-off relay's armature prevented from fluttering, substantially as described.
19. In a telephone system, the combination with a subscriber's line, of a direct-current type of cut-off relay connected with the line, a high-resistance polarized call-bell at the subscriber's station, a source of direct current in series with a source of fluctuating current and means to connect the same in multiple with the call-bell and cut-off relay in the use of the line, whereby the call-bell is rung and the cut-off relay's armature prevented from fluttering, substantially as described.
20. In a telephone system, the combination with a telephone-line extending to a subscriber's station, of a cut-off relay grounded from one side of the circuit, a call-bell grounded from the same side of the circuit and in parallel with the cut-off-relay winding, and means in the call-bell circuit to prevent excessive current from interfering with the bell's operation, a suitable source of current to operate the call-bell and a suitable source of current to operate the cut-off relay, the two sources of current being connected in series with each other and bridged with the cut-off relay and call-bell, whereby the call-bell is rung and the cut-off relay's armature prevented from fluttering in the act of calling the subscriber, substantially as described.
21. In a telephone system, the combination with a telephone-line extending in two limbs

- to a subscriber's station, of a direct-current type of cut-off relay grounded from one limb of the line, a polarized call-bell grounded from the same limb of the line and in multiple with the cut-off-relay winding, and means in the call-bell circuit to prevent excessive current from interfering with the bell's operation, a source of alternating current bridged with the line to actuate the call-bell and cut-off relay 50
- in multiple in the use of the line, and a source of direct current in series with the alternating current to energize the cut-off relay while the alternating current is reversing, substantially as described.
22. The combination with a telephone-line and a connection-terminal for the line normally disconnected therefrom, of a relay for connecting the connection-terminal with the line, a high-resistance polarized call-bell bridged 55
- with the line and adapted to be connected in multiple with the relay in the use of the line, a source of alternating current adapted to be connected with the connection-terminal for operating the call-bell and relay in multiple
- 25 in the use of the line, and a source of direct current in series with the alternating-current source to hold up the relay's armature while the alternating current is reversing, substantially as described.
23. The combination with a telephone-line and a connection-terminal for the line normally disconnected therefrom, of a relay for connecting the connection-terminal with the line when the relay is energized, a polarized call- 60
- bell connected with the line and in multiple with the relay-winding in the use of the line, and means in the call-bell circuit to prevent excessive current from interfering with the bell's operation, means connected with the 65
- connection-terminal to actuate the call-bell and relay simultaneously, the means consisting of a suitable source of current to actuate the relay, and a suitable source of current to actuate the call-bell, the two sources of current being connected in series with each other 70
- 40 and in multiple with the call-bell and relay in the use of the line, substantially as described.
- 45
24. The combination with a telephone-line having a limb extending to a central office, of a line-contact for said line normally disconnected therefrom, a call-bell and condenser in series with said telephone-line, a cord-circuit and connection-plug, a relay to automatically connect the line-contact with said line 75
- and the call-bell and condenser in multiple with the relay, means included in said cord-circuit to actuate said relay and call-bell in multiple simultaneously, said means comprising a source of direct current in series with a 80
- source of fluctuating current, substantially as described.
25. The combination with a telephone-line and a connection-terminal therefor normally disconnected therefrom, of a relay for connecting the connection-terminal with the line, a call-bell and condenser bridged with the line and adapted to be connected in multiple with the relay when the relay is energized, a source of non-continuous potential connected with the connection-terminal to energize the relay and call-bell simultaneously, and a source of current in series with the non-continuous potential to maintain said relay energized while the non-continuous potential is inoperative on 85
- the relay, substantially as described.
26. In a telephone system, the combination of a subscriber's line, a cut-off relay for the line, a call-bell and condenser at the subscriber's station, means to connect the cut-off relay in multiple with the call-bell and condenser, a source of non-continuous potential bridged with the line to actuate the relay and charge and discharge the condenser through the call-bell, and a source of current in series 90
- 80 with the non-continuous potential to maintain current through the cut-off relay when the non-continuous potential is inoperative on the cut-off relay, substantially as described.

In witness whereof I have hereunto subscribed my name in the presence of two witnesses.
